UNITED STATES PATENT OFFICE.

JOHN F. O'CONNOR, OF CHICAGO, ILLINOIS, ASSIGNOR TO CLIFFORD W. SHERMAN, OF BUFFALO, NEW YORK.

CAR-BOLSTER.

976,206.

Specification of Letters Patent. Patented Nov. 22, 1910.

Application filed May 26, 1910. Serial No. 563,547.

To all whom it may concern:

Be it known that I, JOHN F. O'CONNOR, a citizen of the United States, residing in Chicago, in the county of Cook and State 5 of Illinois, have invented a new and useful Improvement in Car-Bolsters, of which the following is a specification.

My invention relates to improvements in the construction of bolsters for cars.

10 The object of my invention is to provide a cast steel car bolster of a simple and efficient construction which will have a maximum strength for the amount or weight of metal therein and which will at the same 15 time be of such form as to enable it to be readily and cheaply cast in wet sand or without cores.

My invention consists in the novel constructions and features herein shown and 20 described and more particularly specified in the claims.

In the accompanying drawing forming a part of this specification, Figure 1 is a side elevation partly in central, vertical, longitudinal section of a car truck and body bolsters embodying my invention; Fig. 2 is a detail plan view of the body bolster; Fig. 3 is a detail plan view of the truck bolster; Figs. 4 and 5 are detail cross sections on 25 lines 4—4 and 5—5 of Fig. 1; Fig. 6 is a side elevation partly in central vertical longitudinal section illustrating a modification; Fig. 7 is a plan view of the truck bolster shown in Fig. 6 and Figs. 8, 9 and 30 10 are cross sections on lines 8—8, 9—9 and 10—10 respectively of Fig. 7.

In the drawing 1 represents the body bolster and 2 the truck bolster. Each of the bolsters 1 and 2 are made of cast steel 40 and are of a general truss shape, that is to say, deeper at the middle than at the ends. Each comprises a central, longitudinal bottom web upwardly inclined from the middle toward each end, a pair of central, longitudinal, upright webs, a pair of horizontal side webs extending longitudinally from end to end of the bolster and a pair of depending upright side webs or flanges, all the webs being integrally connected together and preferably of uniform, or substantially uniform thickness. The central longitudinal web in connection with the central upright and longitudinally extending webs form a central longitudinal open channel 45 between them and the upper horizontal 50

side webs in connection with the intermediate and side upright webs form a pair of open channels at each side of the bolster. By this form and disposition of the metal the greatest possible strength is secured for 55 the amount or weight of metal employed and at the same time the bolster is adapted to be cast in wet sand or without cores thus enabling it to be economically manufactured, and, as all the webs upright and horizontal of the bolster are of uniform thickness, little difficulty is experienced in the casting operation from unequal cooling or contraction or from casting strains.

The body bolster 1 has a central longitudinal bottom web 3 inclined upwardly from the middle portion 4 of the bolster toward each end and a pair of central or intermediate upright webs 5 each extending from end to end of the bolster and of tapering width 60 or depth being wider at the middle portion 65 than at the ends. The body bolster also has a pair of narrow horizontal webs 6 extending from end to end of the bolster and also a pair of depending upright side webs 7 70 which extend from end to end of the bolster and taper from the middle portion thereof toward each end. The body bolster by its integral webs 3, 5, 6, and 7 has a central longitudinal channel 8 and two longitudinal 75 side channels 9, 9 extending from end to end of the bolster, the channels 8, 9 being deeper at the middle than at the end portions of the bolster and all these channels being open, one upwardly and the other two 80 downwardly, so that no cores are required 85 in casting the bolster. The central longitudinal bottom web 3 of the bolster is provided with transverse bends therein to form the side bearing members or projections 90 95 At its middle the body bolster 1 is also provided with a center plate seat or bearing 11. The truck bolster 2 is of the same general shape and construction as the body bolster and comprises a central longitudinal 100 bottom web 13 upwardly inclined from the middle toward each end, a pair of upright webs 14 extending from end to end of the bolster and tapering from the middle toward each end, a pair of horizontal side webs 15 105 and a pair of depending upright side webs 16. The bottom web 13 and upright webs 14, 14 form a central longitudinal open channel 17 and the webs 14, 15, 16 form on each side an open side channel 18. The horizon-

110

tal side webs 15 of the truck bolster are also provided with holes 19 for bolts 20 of the side bearing members 21 on the truck bolster. The truck bolster also has at its middle a center bearing plate 22.

In the modification illustrated in Fig. 6 the construction is substantially the same as that hereinbefore described excepting that transverse fillets 23 are provided at intervals 10 between the upright and horizontal webs and transverse fillet or brackets 24 between the upright webs. As in my invention the bottom or tensile acting web 3 extends transversely in a horizontal line and as the upper 15 or compression side webs 6, 6 also extend horizontally the metal in these webs is all disposed as far as possible from the center or neutral axis of the truss or bolster thus giving it a maximum of strength for the amount or weight of metal, and as in my invention the upright webs are all substantially parallel the disposition of metal in them is also disposed in the most effective manner for strength, while at the same time 20 the bolster is of such form in cross section at all points of its length that the channels formed by the upright and horizontal webs are all open either upwardly or downwardly to give proper draw and thus enable the bolster to be cast entirely without cores. The above also applies fully to the truck bolster. The truck bolster is provided with integral side lugs 25 to receive the truck guides.

As in my invention the upper horizontal side webs 6 of the body bolster are widely separated or spaced apart from each other by the wide bottom web 3, the longitudinal sills of the car have an extended bearing on the body bolster which not only materially adds to the effective strength of the sills but also materially diminishes the strains on the bolts by which the bolster is connected to the sills and which resist the heavy shocks that tend to twist or turn the bolster in respect to the sills. The widely separated horizontal side webs 6, 6 are furnished with holes 26 to receive the bolts for connecting the bolster to the car sills.

I claim:—

1. A bolster consisting of an integral casting comprising a pair of straight horizontal side webs extending from end to end of the bolster, a central bottom web horizontal in cross section and extending from end to end of the bolster and upwardly inclined from the middle toward each end, a pair of central or intermediate upright webs connecting said horizontal side webs with said transversely horizontal bottom web and tapering in depth from the middle toward each end of the bolster, and a pair of depending upright side webs tapering in depth from the middle toward each end of the bolster, said upright webs forming a plurality of open drawable channels between them extending

from end to end of the bolster, substantially as specified.

2. A bolster consisting of an integral casting comprising a pair of straight horizontal side webs extending from end to end of the bolster, a central bottom web horizontal in cross section and extending from end to end of the bolster and upwardly inclined from the middle toward each end, a pair of central or intermediate upright webs connecting said horizontal side webs with said transversely horizontal bottom web and tapering in depth from the middle toward each end of the bolster, and a pair of depending upright side webs tapering in depth from the middle toward each end of the bolster, said upright webs forming a plurality of open drawable channels between them extending from end to end of the bolster, said bottom web having a transverse bend therein to form an integral side bearing member, substantially as specified.

3. A bolster consisting of an integral casting comprising a pair of straight horizontal side webs extending from end to end of the bolster, a central bottom web horizontal in cross section and extending from end to end of the bolster and upwardly inclined from the middle toward each end, a pair of central or intermediate upright webs connecting said horizontal side webs with said transversely horizontal bottom web and tapering in depth from the middle toward each end of the bolster, said upright webs forming a plurality of open drawable channels between them extending from end to end of the bolster, said bottom web having an integral center plate seat at its middle portion, substantially as specified.

4. A bolster consisting of an integral casting comprising a pair of straight horizontal side webs extending from end to end of the bolster, a central bottom web horizontal in cross section and extending from end to end of the bolster and upwardly inclined from the middle toward each end, a pair of central or intermediate upright webs connecting said horizontal side webs with said transversely horizontal bottom web and tapering in depth from the middle toward each end of the bolster, and a pair of depending upright side webs tapering in depth from the middle toward each end of the bolster, said upright webs forming a plurality of open drawable channels between them extending from end to end of the bolster, said bolster having at intervals transverse fillets connecting said upright and horizontal webs, substantially as specified.

5. The combination of a cast steel body bolster comprising a pair of horizontal webs extending from end to end of the bolster, a central bottom web transversely horizontal, extending from end to end of the bolster and upwardly inclined from the

middle toward each end, a pair of upright intermediate webs connecting said horizontal side webs and said bottom web and a pair of depending upright side webs with a cast steel truck bolster comprising a pair of horizontal side webs extending from end to end of the bolster, a bottom web transversely horizontal extending from end to end of the bolster and upwardly inclined from the middle toward each end, a pair of upright intermediate webs and said bottom web and a pair of depending upright side webs, said upright webs forming a plurality of open drawable channels between them extending from end to end of the bolster, substantially as specified.

6. The combination of a cast steel body bolster comprising a pair of horizontal side webs extending from end to end of the bolster, a bottom web transversely horizontal extending from end to end of the bolster and upwardly inclined from the middle toward each end, a pair of upright intermediate webs and said bottom web and a pair of depending upright side webs with a cast steel truck bolster comprising a pair of horizontal side webs extending from end to end of the bolster, a bottom web transversely horizontal extending from end to end of the bolster and upwardly inclined from the middle toward each end, a pair of upright intermediate webs connecting said side webs and said bottom web and a pair of depending upright side webs, said bolsters having integral center plate seats at their middle, said upright webs forming a plurality of open drawable channels between them ex-

tending from end to end of the bolster, substantially as specified.

7. An integral metal beam comprising a pair of horizontal side webs extending from end to end, a central web, horizontal in cross section and extending from end to end, a pair of intermediate upright webs connecting said side and central webs, said upright webs forming a plurality of open drawable channels between them extending from end to end of the bolster, substantially as specified.

8. An integral metal beam comprising a pair of horizontal side webs extending from end to end, a central web, horizontal in cross section and extending from end to end, a pair of intermediate upright webs connecting said side and central webs, and a pair of upright webs forming a plurality of open drawable channels between them extending from end to end of the bolster, substantially as specified.

9. The integral cast metal beam comprising a pair of horizontal side webs extending from end to end, a central web, horizontal in cross-section extending from end to end and inclined from the middle toward each end, a pair of intermediate upright webs connecting said side and central webs and tapering in depth from the middle toward each end and a pair of upright side webs tapering in width from the middle toward each end, substantially as specified.
